UNITED STATES PATENT OFFICE.

MABEL WOODS HINRICHES, OF CHICAGO, ILLINOIS, ASSIGNOR TO BURLEY & TYRRELL COMPANY, OF CHICAGO, ILLINOIS, A CORPORATION OF ILLINOIS.

DESIGN FOR AN ARTICLE OF MANUFACTURE.

46,127.

Specification for Design.

Patented July 21, 1914.

Application filed April 22, 1914. Serial No. 833,816. Term of patent 14 years.

To all whom it may concern:

Be it known that I, MABEL Woods HINRICHES, a citizen of the United States, residing at Chicago, in the county of Cook and State of Illinois, have invented a new, original, and ornamental Design for an Article of Manufacture, of which the following is a specification, reference being had to the accompanying drawing, forming a part thereof.

The figure is a plan view showing my new design for an article of manufacture.

I claim—

The ornamental design for an article of manufacture as shown.

MABEL WOODS HINRICHES.

Witnesses:

T. B. HINRICHES,
JOHN A. STOELLER.
